 United Shoe Machinery Corporation, Flemington, N. J., a corporation of New Jersey

Application June 28, 1946, Serial No. 680,013

15 Claims. (Cl. 12—10)

1

This invention relates to machines for lasting shoes, and is herein illustrated as embodied in a machine for progressively tensioning an upper over a last and for securing the upper in lasted position to an innersole with an adhesive and in which the shoe is automatically fed along, step by step, to present successive portions of the upper to the action of the lasting instrumentalities. It is to be understood, however, that the invention is not limited to use in machines for lasting shoe uppers, but is of broader utility, being particularly well adapted for use in machines for performing other analogous shoemaking operations, such, for example, as the so-called lasting of the platform covers of slip-lasted shoes, and that features of the invention are applicable to lasting machines in which the work is fed along by an operator instead of automatically.

An object of this invention is to provide an improved lasting machine of the type mentioned above which is of relatively simple and inexpensive construction, easy to operate and yet extremely efficient and speedy in action.

With this end in view, and in accordance with a feature of this invention, the herein illustrated machine, which has a gripper for exerting a pull on the lasting margin of an upper, in a direction perpendicular to the bottom of a shoe, to tension the upper, and movable, while exerting this pull, in a direction to feed the work, is provided with means, located on opposite sides of the gripper and movable with the gripper in the direction of feed, for engaging the bottom of the shoe to support it against said pull. As embodied in the illustrated machine, these means comprise a shoe bottom rest and a presser member, the former arranged to engage the bottom face of the innersole at a point located rearwardly, in the direction of feed, of the gripper, and the latter adapted to bear against the shoe bottom in front of the gripper. In this manner, any tendency of the shoe to twist or turn, in response to the pull applied to the upper, is obviated, and the application of the pull in a direction perpendicular to the shoe bottom is assured. Moreover, with the shoe supported in the manner explained, the pull of the gripper itself tends to hold the shoe in the proper position and no extra effort on the part of the operator is required. Preferably, and as herein illustrated, the shoe-bottom rest is arranged to engage the innersole at the marginal edge thereof, and adjacent to the point at which the pull of the gripper is applied, so as to prevent lifting of the innersole during the tensioning of the upper. Also, during the back-feeding movement of

2

the gripper the shoe-bottom rest slides over and smooths out the edge of the innersole.

After the upper has been tensioned, its lasting margin is secured adhesively in lasted position to the innersole and, in accordance with another feature of the invention, this is accomplished by means of a reciprocating wiper that wipes the lasting margin of the tensioned upper inwardly from the edge of the shoe bottom and presses it firmly against the bottom face of the innersole and a presser member which is arranged to apply additional pressure to a portion of the lasting margin adjacent to that engaged by the wiper. Preferably, and in the herein illustrated machine, this presser member is arranged to deliver a hammer-like blow to the lasting margin, thereby facilitating adherence to the innersole. Also, this pressure member is adapted to move the shoe away from the wiper thereby relieving the pressure of the wiper against the lasting margin during the return movement of the wiper, so that any tendency for the wiper, when moving in this direction, to outwipe a part of the lasting margin previously wiped in and secured to the innersole, is eliminated. To facilitate the entrance of the lasting margin into the open gripper jaws, the reciprocating wiper is provided with a finger for deflecting the upper into the jaws.

In the herein illustrated machine, the feeding increment of the gripper is relatively short and, in accordance with a still further feature of the invention, the wiper and presser member are so constructed and arranged that their combined action is substantially coextensive with this feeding increment. Thus, substantially every portion of the lasting margin, after being tensioned, is pressed firmly against the bottom of the shoe and securely adhered to the innersole.

These and other objects and features of the invention will become apparent from the following detailed description of the embodiment illustrated in the accompanying drawings, and will be pointed out in the claims.

45 In the drawings,

Fig. 1 is a view, in side elevation and with certain parts in section, of a machine embodying this invention;

Fig. 2 is a plan view of the machine shown in Fig. 1 with the cover portion of the head removed to show the mechanism contained therein;

Fig. 3 is a view in front elevation of the machine shown in Fig. 1 and with a portion of the head cover broken away;

Fig. 4 is a view, in side elevation and at an en-

larged scale, of parts of the operating mechanism of the machine;

Fig. 5 is a view in side elevation of other parts of the operating mechanism;

Fig. 6 is a view in end elevation of a part of the operating mechanism shown in Fig. 4;

Figs. 7 and 8, 9 and 10, and 11 and 12 are views of the operating elements of the machine, in plan and in side elevation respectively, and showing these elements in different positions assumed during the operation of the machine.

Referring now to the drawings, the operating instrumentalities of the illustrated machine comprise a gripper, having an upper jaw 20 and a lower jaw 22, for seizing and tensioning the stock and for feeding the shoe, a reciprocating wiper 24 for wiping the lasting margin of the tensioned stock inwardly from the edge of the bottom of a shoe and for pressing the overwiped lasting margin against the bottom of the shoe, and a presser member 26 for applying additional pressure to the overwiped lasting margin of the stock and for relieving the pressure of the wiper 24 against the stock during the return movement of the wiper. During the operation of these instrumentalities, the shoe being lasted is supported against the pull of the gripper by means of a shoe-bottom rest 28 and also, as will be explained below, by the presser member 26, and is guided and positioned with respect to the lasting instrumentalities by means of an edge gage comprising a pair of anti-friction rolls 30, 30. The above instrumentalities are associated with a hollow head 32 having a cover 34 and supported on a column 36 of suitable height. The mechanism for operating the lasting instrumentalities is contained within the hollow head portion 32.

The upper-gripping jaw 20 is secured, by means of screws 40, 40, to the front end of a slide 42, that is mounted in a guideway 44 formed in a radially extending portion 46 of a hub 48, see Figs. 1, 4 and 6. This hub has an integrally formed post 50 extending downwardly therefrom that is journaled in bearing bushings 52, 54, fitted into bores in portions of the head 32, a thrust collar 56 being provided to hold the parts in the positions shown in Fig. 4. The lower gripper jaw 22 is secured, by means of screws 60, 60, to a curved arm 62 which passes through an opening in the slide 42 to which it is pivoted on a pin 64. Above this pin, the arm 62 has an upwardly extending tubular portion 66 that is provided with a bore 68, see Fig. 4. Slidably mounted in the lower end of this bore is a plunger 70 having a rounded end that bears on an inclined surface 72 formed on the slide 42. This plunger is held against rotation in the bore 68 by means of a cross pin 74 which extends through slots 76, 76 in the tubular portion 66, and is urged downwardly to turn the arm 62 in a clockwise direction about the pin 64, see Fig. 4, and thus close the jaws 20 and 22, by means of a compression spring 78. This spring bears at its lower end on a thrust washer 80 which rests on the ends of the pin 74 and at its upper end on a thrust washer 82 which is supported against an adjusting nut 84 threaded to an extension 86 of a plug 88 that is secured to the upper end of the tubular portion 66. The force exerted by the spring 78, and therefore the closing pressure of the jaws 20 and 22 and intensity of the pull exerted by the jaws, may be varied by means of the adjusting nut 84 which is thereafter held in adjusted position by means of a lock nut 90.

For moving the jaw 22 away from the jaw 20, 75

to open the jaws, a toggle comprising links 92 and 94 is provided, the link 92 being pivoted to the upper end of the arm 62 and the link 94 being pivoted to a post 96 that extends upwardly from the slide 42. The link 94 has a bifurcated end which is connected to the link 92 and at this end the link is shaped to present two flat bearing surfaces 98, 98 for engagement with means for straightening the toggle to open the jaws, see Fig. 2. Two such means are provided, one of which is actuated automatically during the operation of the machine while the other is actuated by the operator to open the jaws for the insertion of the stock at the beginning of a lasting operation.

The automatically actuated means comprises a roll 100 that is carried by an arm 102 which is rotatably mounted on a shaft 104, journaled in bearings formed in the housing 32, see Figs. 1, 2 and 4. This arm is swung, periodically during the operation of the machine and in a counterclockwise direction, to cause the roll 100 to straighten the toggle 92, 94, and open the jaws, by means of a second arm 106, likewise mounted for rotation on the shaft 104 and connected to the arm 102 by means of two links 108 and 110. The arm 106 is actuated from a cam track 112 formed on a cam 114, carried by the main drive shaft 116 of the machine, by means of a cam lever 118 and an adjustable connecting rod 120, see Fig. 4. For the purpose of avoiding pounding of the roll 100 on the surface 98, a light spring 122 is stretched between a pin 124, connecting the links 108 and 110 and a pin 126 supported on the arm 106. With this arrangement, as the arm 106 is swung in a clockwise direction and the toggle, 92, 94 broken, first by means of a spring plunger 128 on the slide 42, and then by the spring 78, the spring 122 will hold the roll 100 in contact with the surface 98 by breaking the toggle formed by the links 108 and 110. It will be understood that the spring 122 is relatively weak so that, even with the mechanical advantage afforded by the action of the last-mentioned toggle, it is readily overcome by the gripper-closing spring 78.

The means for opening the jaws 20 and 22, which is actuated by the operator, comprises a roll 130 which is carried by an arm 132 secured to the shaft 104, by means of a setscrew 134, see Fig. 2. The shaft 104 extends at one end beyond the head 32 and on this end there is secured an arm 136 which is connected, by means of a link 138, to an arm 140 which is secured to a shaft 142 journaled in and extending across the hollow head portion 32. Secured to this shaft 142 is a second arm 144 from which a treadle rod 146 extends downwardly to a treadle, not shown. When the treadle is depressed, against the action of a treadle spring, not shown, the arm 136 will be rotated in a counterclockwise direction, as viewed in Fig. 1, so that the roll 130 will be moved downwardly against a surface 98, see Fig. 2, to straighten the toggle 92, 94 and thus move the jaw 22 away from the jaw 20. When this toggle is thus straightened by means of the treadle, the roll 100 will remain in contact with the other surface 98, due to the action of spring 122 and the toggle comprising the links 108 and 110 in the manner explained above, with the result that, when the treadle is released, this surface 98 will not strike the roll 100 a blow as the toggle 92, 94 is broken and the gripper jaws opened.

The slide 42 is reciprocated to cause the gripper jaws 20 and 22 to exert a pull in a direction perpendicular to the bottom of a shoe to tension

the upper, by means of mechanism about to be described. A link 150 is connected at one end to a ball joint carried by the slide 42 and at its other end to a similar ball joint 154 mounted in the upper end of a rocker arm 156, see Fig. 4. This rocker arm is pivotally mounted on a stud 158, see Figs. 1 and 4, supported on a removable back plate 160 that is secured in place on the head 32 by means of screws 162, see Fig. 1. The arm 156 has a counterbalance portion 164 that extends below the stud 158 and pivoted to the upper end of this arm is a link 166 that is adjustably connected, by means of an arcuate slot 168 and a clamp nut 170, to a cam lever 172. This cam lever is pivotally mounted on a cross shaft 173 that is supported in bosses 174 and 176, Fig. 2, formed on the head 32 and held in position by means of a setscrew 178. Beneath this shaft, the lever 172 is enlarged to provide a counterbalance portion 180 and projecting from the lower side of the counterbalance portion is an ear 182 which carries a cam roll 184. The cam roll 184 engages a cam groove 186 formed in the side of a second cam 188 which is mounted on the main drive shaft 116, see Figs. 2 and 4. The counterbalance portion 180 is cut away at 190, to clear the boss 174 and at 192 to clear the cam 114, see Figs. 1, 2 and 4. The cam track 186 is shaped to effect oscillation of the cam lever 182 and also of the arm 156, and thus to cause the slide 42 to be reciprocated back and forth in the guideway 44 formed in the portion 46 that extends from the hub 48. The timing of the actions of the cam grooves 112 and 186 is such that the gripper jaws 20 and 22 are moved to the right, Figs. 1, 2 and 4, while they are held closed by the spring 78. By loosening the nut 170, the position of link 166 may be altered so as to change the range of movement of the slide 42 and thus vary the extent of pull applied by the gripper jaws 20 and 22. As has already been explained above, the intensity of the pull may be varied by adjusting the tension of the spring 78.

For moving the gripper jaws 20 and 22 laterally, while they are closed and exerting tension on the stock, thereby to effect a feeding movement of the shoe, the hub 48, which carries the extending portion 46 in which the slide 42 is mounted, is oscillated in time relation to the closing of the jaws and the reciprocation of the slide 42, by means of the following mechanism. A link 200 is pivotally connected at one end to the extending portion 46 by means of a stud 202, see Fig. 4, and at its other end is adjustably secured to a rocker arm 204, by means of a clamp bolt 206 and an arcuate slot 208 formed in the arm 204, see Fig. 2. The arm 204 has a hub member 210 that is journaled on a shaft 212 supported in extending portions 214 and 216 of the head 32, see Fig. 1, and also carries a cam roll 218 which engages a cam groove 220 that is formed in the periphery of the cam 114, mentioned above, see Fig. 2. By loosening the clamp bolt 206, the position of the link 200 may be altered and the range of lateral movement of the gripper jaws varied thus to change the extent of feeding movement imparted to the work.

The wiper 24 comprises a relatively narrow finger projecting downwardly from a plate 230 that is adjustably mounted on the end of an arm 232, by means of a bracket 234 and screws 236, 238, see Figs. 1, 2 and 5. The plate 230 has an end 240 which extends beyond the bracket and on the lower side of this end is a curved finger 241 adapted to serve as a deflector for guiding

the lasting margin of stock into the gripper jaws, see Figs. 5, 7, 9 and 11. The arm 232 is provided with a hub 242 which is journaled on a stud 244 supported on the head 32, and from this hub there extends a second arm 246 carrying a cam roll 248. This cam roll runs in a cam groove 250, formed in a cam 252 which is mounted on the main drive shaft 116. This cam groove is so shaped as to effect oscillation of the arms 232 and 246 and reciprocation of the wiper 24 in time relation to the tensioning and feeding actions of the gripper jaws 20 and 22 in a manner to be explained below.

The pressure member 26 is pivotally mounted on the outer end of a bracket 260 by means of a stud 262, Figs. 5, 7, 9 and 11, and a spring-pressed plunger 264, aligned with the axis of the stud, yieldingly holds the presser member in the position shown in Fig. 5 while at the same time permitting it to rock about the stud 262 and to lie flatly on the bottom of a shoe even if the latter is tipped as shown in Fig. 10. The bracket 260 is adjustably secured, by means of a screw 266, to the front end of a slide 270 which is mounted in a guideway 272 formed in the extending portion 46 of the hub 48, see Figs. 5 and 6. For reciprocating this slide, to move the presser member toward and away from the bottom of a shoe being operated upon in the machine, a link 280 is connected to the back end of this slide, by means of a ball joint 282, and also to the upper end of a lever 284, by means of a ball joint 286. This lever is rotatably mounted on the shaft 173 and carries, at its lower end, a cam roll 288 which runs in a cam groove 290 formed in the cam 252. This cam groove is shaped to effect reciprocation of the presser member in time relation to the actions of the wiper 24 and of the gripper jaws 20 and 22 in a manner to be presently explained.

The shoe bottom rest 28 is adjustably mounted on the hub 48 by means of screws 296, see Figs. 1 and 4. The edge gage rolls 30, 30 are journaled on studs carried by a bracket 300 which is adjustably mounted on a forwardly projecting portion of the cover 34, by means of a screw 302, see Figs. 1, 8, 10 and 12. The cover is hinged on a rod 304 which passes through ears 306, 306 on the head 32 so that it may be lifted to open the head for inspection or adjustment of the operating mechanism contained therein. To thus open the head, the cover 34 is swung through an angle of about 120° in a clockwise direction from the position in which it is shown in Fig. 1 and is held in this open position by means of a toggle linkage comprising interconnected links 310 and 312, connected respectively to the cover and to the head. When the cover is closed it rests on the head along the line a, Figs. 1 and 3, and there is an opening 314, formed partly in the cover and partly in the head, through which the operating elements of the machine project. The lower portion of the head forms a reservoir for oil which is picked up by the rotating cams 114 and 252 and thrown up over the operating mechanism to lubricate it.

For holding the cover in closed position, two locking plungers 316, 318 are provided and these plungers are slidably mounted in bores formed in bosses 320, 322 extending from a yoke 324 that is secured to the cover by means of screws 326, see Fig. 3. These plungers are withdrawn from, or projected into, cooperating grooves 328, 330, formed in bosses 332, 334, respectively, and extending upwardly from the head 32, by means of

a knob 340 carried by a rod 342. This rod is slidably mounted in a bore 344 in the forwardly projecting portion of the cover and from it a link 346 extends rearwardly to an arm 348 of a bell-crank lever 350. This bell-crank lever is rotatably mounted on the yoke 324 and, beneath the arm 348, is provided with two other arms which are connected respectively to the plungers 316 and 318 by means of links 352, 354. The arrangement is such that when the knob is pulled to the left, Fig. 1, the plungers are withdrawn from their cooperating grooves 328, 330 and the cover is released for opening. Return of the knob 340, to the position shown in Fig. 1, projects the plungers into the grooves, thus locking the cover in closed position. A ball detent 356 cooperates with spaced grooves 358, 360 in the rod 342 to hold the knob in either of the two positions just mentioned.

The main drive shaft 116, which is journaled in suitable anti-friction bearings carried by the head, only one of which is shown at 370, Fig. 2, projects at one end beyond the side wall of the head. On this end of the shaft there is mounted a belt pulley 372 to which power is supplied from a suitable source, not shown, by means of a belt 374.

The individual function of each of the several operating elements of the illustrated machine having been described above, their cooperative action, when the machine is used to last a shoe, will now be explained. Referring particularly to Figs. 7 to 12 inclusive, the machine is there shown as lasting the upper U of a shoe S, assembled, together with an innersole I, on a last L. After opening the jaws 20 and 22, by depressing the treadle, not shown, that is connected to the rod 146, the operator then inserts the lasting margin of the upper between these open jaws, see Figs. 11 and 12. Upon release of the treadle, these jaws close and grip the lasting margin of the upper, see Fig. 8. At this point in the cycle of the operation of the machine, the presser member 26 has been moved to a forward position, a little beyond the front end of the bottom rest and substantially in line with the operating face of the wiper 24 which is now in its down position and extending over the bottom of the shoe, see Figs. 7 and 8. The shoe is held by the operator with its bottom face bearing against the presser member 26, at one side of the gripper jaws 20 and 22, and against the bottom rest 28, at the other side of the gripper jaws, and with its side face in engagement with the edge gage rolls 30, 30.

As soon as the gripper jaws have closed on the upper they are moved rearwardly, to the right in Fig. 8, together with the slide 42 which is actuated by means of the cam 186, to tension the upper, the pull of the gripper jaws being sustained by the presser member 26, on one side of the gripper, and by the bottom rest 28, on the other, so that there is no tendency to twist the shoe. During this tensioning action of the gripper jaws, the wiper is elevated, by means of the cam 250, and the gripper jaws are moved laterally, to feed the shoe, together with the presser member 26 and the bottom rest 28, by means of the cam 220 which oscillates the hub 48 and the portion 46 extending therefrom. Before the wiper is elevated, the presser member is moved forwardly a small distance and just enough to relieve the pressure of the wiper against the shoe bottom, thus preventing the wiper 24 from out-wiping the margin of the upper which has just been wiped-in and pressed against the bottom face of the innersole I. Figs. 9 and 10 show the

parts in the positions assumed at the completion of the feeding movement of the gripper jaws; the longitudinal axes of the slide 42, arm 270 and bottom rest 28 now being in alignment with a vertical plane passing through the center of the machine.

Next the wiper 24 descends, and just as it engages the margin of the upper, still gripped by the jaws 20 and 22, see Fig. 10, these jaws open to release the margin of the upper which is immediately wiped inwardly from the edge of the shoe bottom. As the wiper starts to descend, the presser member 26 is retracted so that the margin of the upper is pressed firmly against the bottom face of the innersole I by the wiper. It will be understood that the margin of the upper U and/or the bottom face of the innersole I will have been previously coated with adhesive so that the pressure applied by the wiper will secure the margin to the platform in lasted position. As the wiper completes its wiping action, the finger 241 will engage the lasting margin of the upper ahead of the gripper and bend it into a position to enter the open jaws. During this wiping action and after the presser member has started to move back, the gripper jaws, presser member and bottom rest are returned to their original positions, see Figs. 11 and 12, the bottom rest now sliding over the bottom face of the innersole and the shoe being held against retrograde movement by virtue of the pressure of the wiper against the overlasted margin of the cover. The presser member is moved forwardly very rapidly so as to strike the overlasted margin of the upper, adjacent to the wiper, a sharp hammer-like blow which very effectively secures the lasted margin in lasted position.

The feeding increment of the gripper jaws is relatively short, in the order of about $\frac{1}{4}$ of an inch, and the lengthwise extent of the combined pressing actions of the wiper 24 and presser member 26 is substantially coextensive with this feeding increment. Accordingly, the area of the lasting margin of the upper U that is engaged by the wiper 24 and presser member 26 is substantially coextensive with this feeding movement. Thus substantially every portion of the lasting margin, in a lengthwise direction along the edges of the shoe bottom, is not only subjected to the tensioning action of the gripper jaws 20 and 22, but also is pressed firmly against the bottom of the shoe, either by the wiper 24 or by the presser member 26. Accordingly, the lasting margin of the upper U is everywhere bonded firmly to the innersole I. This action is greatly augmented by the hammer-like pounding effect of the presser 26.

Because of the small feeding increment of the gripper jaws the tensioning action of the grippers is evenly distributed along the edges of the shoe bottom and each tensioned portion is laid smoothly over the shoe bottom and secured firmly to the innersole by the combined actions of the wiper 24 and presser member 26. However, because of the simplicity of the mechanism and arrangement of the parts, the machine may be operated at a high speed and a rapid production rate obtained. At each point at which tension is applied by the gripper jaws, the innersole is held against the last by the bottom rest 28 and lifting of the innersole is prevented. Also, during the back-feeding movement of the gripper jaws, the bottom rest slides over the innersole and smooths it down.

Referring to Fig. 8, a shoe being lasted should be held with its bottom in a substantially vertical

plane. However, should the operator inadvertently tip the shoe, as illustrated in Fig. 10, the machine will still operate satisfactorily, since the leading end of the wiper 24 is rounded and the presser member 26 is self-leveling due to its pivotal connection to the bracket 260.

Having described my invention, what I claim as new and desire to secure by Letters Patent of the United States is:

1. A lasting machine having, in combination, means for seizing the lasting margin of stock to be lasted and for exerting a pull in a direction perpendicular to the bottom of a shoe, said means being movable, while exerting said pull, in a direction to feed the shoe, and means for engaging the bottom of the shoe at opposite sides of said first-named means to support the shoe against said pull, said last-named means being movable with the first-named means during the feed of the shoe.

2. A lasting machine having, in combination, a gripper for seizing the lasting margin of stock to be lasted and for exerting a pull thereon in a direction perpendicular to the bottom of a shoe to tension the stock, said gripper being movable, while exerting said pull, in a direction to feed the shoe, a bottom rest and a presser member for engaging the bottom of the shoe at opposite sides of the gripper, respectively, to support the shoe against said pull, said bottom rest and presser member being movable with the gripper in the direction of feed.

3. A lasting machine having, in combination, an intermittently operating gripper, means for causing said gripper first to close on the lasting margin of stock to be lasted, next to move in a direction perpendicular to the bottom of the shoe to tension the stock, then to move in a direction to feed the shoe, and finally to open and return, a shoe-bottom rest arranged to engage the bottom of the shoe at one side of said gripper, and a presser member for engaging the bottom of the shoe at the other side of said gripper, said shoe-bottom rest and said presser member being movable, in the direction of feed, with said gripper.

4. A lasting machine having, in combination, an intermittently operating gripper, means for causing said gripper first to close on the lasting margin of stock to be lasted, next to move in a direction perpendicular to the bottom of the shoe to tension the stock, then to move in a direction to feed the shoe, and finally to open and return, a shoe-bottom rest adapted to engage the bottom of the shoe at the marginal edge thereof and positioned behind said gripper, in the direction of feed, and a presser member arranged to engage the bottom of the shoe in front of said gripper, in the direction of feed, said shoe-bottom rest and said presser member being movable, in the direction of feed, with said gripper.

5. A lasting machine having, in combination, an intermittently operating gripper constructed and arranged to tension stock, in different locations along the marginal edge of the bottom of a shoe, a reciprocating wiper, operating in time relation to said gripper, for wiping the lasting margin of the tensioned stock inwardly from the edge of the shoe bottom, in each of said locations, and a presser member for thereafter pressing the wiped-in portion of the stock against the shoe bottom in each location, said presser member being arranged to move the shoe away from said wiper and thereby relieve the pressure of the wiper on the stock during the return movement of said wiper.

6. A lasting machine having, in combination, an intermittently operating gripper constructed and arranged to tension stock, in different locations along the marginal edge of the bottom of a shoe, and, while tensioning the stock, to feed the shoe, a reciprocating wiper, operating in time relation to said gripper, for wiping the lasting margin of the stock inwardly from the edge of the shoe bottom, in each of said locations, and a reciprocating presser member, movable toward the bottom of the shoe, for thereafter pressing the wiped-in portion of the stock against the shoe bottom in each location.

7. A lasting machine having, in combination, an intermittently operating gripper constructed and arranged to tension stock, in different locations along the marginal edge of the bottom of a shoe, and, while tensioning the stock, to feed the shoe, a reciprocating wiper, operating in time relation to said gripper, for wiping the lasting margin of the stock inwardly from the edge of the shoe bottom, in each of said locations, and a reciprocating presser member, movable toward the bottom of the shoe, for thereafter pressing the wiped-in portion of the stock against the shoe bottom in each location, said presser member being arranged to move the shoe away from said wiper and thereby relieve the pressure of the wiper on the stock during the return movement of said wiper.

8. A lasting machine having, in combination, means for tensioning stock, in different locations along the marginal edge of a shoe, a reciprocating wiper, operating in timed relation with said tensioning means for wiping the lasting margin of the tensioned stock inwardly from the edge of the shoe bottom and for pressing said lasting margin against the shoe bottom, and means adjacent to said wiper for applying additional pressure to the lasting margin of the stock, said last-named means being arranged to relieve the pressure of the wiper on the stock during the return movement of said wiper.

9. A lasting machine having, in combination, means for tensioning stock, in different locations along the marginal edge of a shoe, and for feeding the shoe, a reciprocating wiper, operating in time relation with said tensioning means, for wiping the lasting margin of the tensioned stock inwardly from the edge of the shoe bottom and for pressing said lasting margin against the shoe bottom, and means adjacent to said wiper for applying additional pressure to the lasting margin of the stock.

10. A lasting machine having, in combination, means for tensioning stock, in different locations along the marginal edge of a shoe, and for feeding the shoe, a reciprocating wiper, operating in time relation with said tensioning means for wiping the lasting margin of the tensioned stock inwardly from the edge of the shoe bottom and for pressing said lasting margin against the shoe bottom, and means adjacent to said wiper for applying additional pressure to the lasting margin of the stock, said last-named means being arranged to relieve the pressure of the wiper on the stock during the return movement of said wiper.

11. A lasting machine having, in combination, means for tensioning stock, in different locations along the marginal edge of the bottom of a shoe, and for feeding the shoe by increments of predetermined length, a wiper for laying the lasting margin of the tensioned stock in over and for pressing it against the bottom of the shoe, in each of said locations, and a presser member, po-

11

sitioned ahead of said wiper in the direction of feed, for applying pressure to the overlaid lasting margin, said wiper and said presser member being so arranged that their combined pressing action is substantially coextensive with said feeding increment.

12. A lasting machine having, in combination, an intermittently operating gripper for tensioning stock, in different locations along the marginal edge of the bottom of a shoe, and for feeding the shoe by increments of predetermined length, a reciprocating wiper having a relatively narrow operating face for wiping the lasting margin of the tensioned stock inwardly from the edge of the shoe bottom and for pressing it against the bottom of the shoe, in each of said locations, and a presser member, positioned close to and ahead of said wiper in the direction of feed, for applying pressure to the overlaid lasting margin, said wiper and said presser member being so arranged that their combined pressing action is substantially coextensive with said feeding movement.

13. A lasting machine having, in combination, means for tensioning stock, in different locations along the marginal edge of the bottom of a shoe, a wiper for laying the lasting margin of the tensioned stock in over and for pressing it against

the bottom of the shoe, in each of said locations, and means associated with said wiper for engaging the lasting margin of the stock to position it with respect to said tensioning means.

14. A lasting machine having, in combination, an intermittently operating gripper comprising a pair of jaws for tensioning the stock, in different locations along the marginal edge of the bottom of a shoe, a reciprocating wiper for wiping the lasting margin of the tensioned stock inwardly from the edge of the shoe bottom and for pressing it against the shoe bottom, in each of said locations, and means associated with said wiper for positioning the lasting margin of the stock with respect to said gripper jaws.

15. A lasting machine having, in combination, an intermittently operating gripper comprising a pair of jaws for tensioning the stock, in different locations along the marginal edge of the bottom of a shoe, and movable in a direction to feed the shoe, a reciprocating wiper for wiping the lasting margin of the tensioned stock inwardly from the edge of the shoe and for pressing it against the bottom of the shoe, in each of said locations, and means associated with said wiper for positioning the lasting margin of the upper with respect to said gripper jaws.

CORWIN W. BAKER.
